ELECTRON DISCHARGE DEVICE OF THE
VELOCITY MODULATION TYPE

John Heaver Fremlin, London, England, assignor,
by mesne assignments, to International Standard
Electric Corporation, New York, N. Y., a
corporation of Delaware

Application October 14, 1942, Serial No. 462,029
In Great Britain December 12, 1941

3 Claims. (Cl. 315—6)

1

The present invention relates to electron discharge devices of the kind in which a beam of electrons is directed across a first high frequency electric field to be velocity modulated thereby and then across a drift space and then across a second high frequency electric field which abstracts energy from the modulated beam. The two electric fields may be coupled together to produce oscillations in known manner.

In the design of such velocity-modulation oscillators for operation at short wavelengths with any considerable efficiency there are two requirements that are difficult to reconcile. Firstly, it is necessary that the electron beam after modulation by small oscillatory fields should be well bunched before crossing the energy-extracting field. This is the case because the losses in any particular circuit are proportional to the square of the amplitude of oscillation. The efficiency of bunching in a circuit of given resonant impedance at the point of application of the electron beam can be determined by measuring the starting current (I_{s1}), or the current necessary for oscillation just to be maintained. If bunching is inefficient this starting current will necessarily be high. In order, therefore, to reduce the effect of losses it is necessary to make the bunching as efficient as possible.

Secondly, it is necessary for the well formed bunch to cross as large as possible a high frequency field in order that direct current energy may be efficiently extracted at the output. This means that a large high frequency field must be obtained in the output circuit without over-bunching of the electron stream by the modulating field. It will be observed that where the ratio of the amplitudes of the modulating and energy extracting fields is fixed this condition clashes with the condition for low starting current described above, since with a large field and low starting electron current, over-modulation would take place. Thus oscillators which start easily would never give a very high efficiency.

These two conditions may be reconciled by reflecting the beam back through the high frequency field in such a way that the beam gives up further energy to the field.

It is the object of this invention to provide electron discharge devices of the kind hereinbefore specified provided with novel reflecting arrangements.

According to the invention these arrangements comprise means for producing along the portion of the path of the electron beam after passing

2

the second high frequency electric field or energy abstracting field, a substantially constant potential positive with respect to the electron source of the beam and at the end of said portion of the beam path a sudden drop in potential to substantially the potential of said electron source.

In this type of reflecting field, the faster electrons take the shorter time to reach the reflecting point and to return to the second high frequency field. The behaviour of an electron in such a field may be likened to a ball thrown against a vertical wall and bouncing back. In this case, the faster the ball is thrown, the more rapidly will it return.

There is one other kind of reflecting field to which, however, the present invention does not relate, namely, a field in which the potential distribution gradually decreases from a positive potential at the second high frequency field to zero or slightly positive or negative potential with respect to the electron source of the beam at some distance from the said second high frequency field. In this case, the slower electrons take the shorter time to reach the reflecting point and return to the second high frequency field, and the behaviour of an electron may be likened to the behaviour of a ball thrown vertically into the air, a constant retardation occurring due to gravity, and the faster the ball is thrown up the longer will it take to return.

The invention will be better understood from the following description of one embodiment, given by way of example and taken in conjunction with the accompanying drawings in which:

Figs. 1a and 1b show diagrammatically in plan and elevation an electron discharge device of the velocity-modulation type described in patent specification No. 2,320,860 issued to John Heaver Fremlin on June 1, 1943.

Figs. 2 and 3 are graphs showing the relationship between the beam current and the efficiency of electron velocity modulated devices of known type; and

Fig. 4 is a similar graph of a device according to the invention.

Referring to Figs. 1a and 1b, one embodiment of the invention comprises a coaxial line type resonator consisting of a length of a coaxial line formed by inner conductor 1 and outer conductor 2. An axial slot is provided through the inner conductor 1 and at diametrically opposite positions in the outer conductor, the slots in the two conductors being in alignment to allow the passage of an electron beam therethrough. This

beam is produced by a cathode 3 and controlling grid 4 situated opposite the slots on one side of the outer conductor. A reflecting electrode 5 is located at the diametrically opposite side of the outer conductor. The width of the gaps A and B are adjusted by means of tips or flanges 6, 7, 8 and 9 as shown. The drift path for the electrons is across the inner conductor 1.

In a coaxial line resonator of this type, which has been described in said patent specification No. 2,320,860, the beam is collected by a collecting electrode in the position 5 and the modulation system satisfies the second condition aforementioned, that is for large input powers a considerable efficiency, of the order of 35% may be obtained. On the other hand, the short drift path used makes the bunching by small fields inefficient and the starting current is high. According to this invention, the collecting electrode is replaced by a reflecting electrode, so that the beam is reflected back across the gaps A and B and the transit time from the gap B to the reflecting electrode 5 and back again to the gap B is arranged to be an odd number of half-cycles of the high frequency field so that the reflected bunch of electrons in the beam will occur at the gap B alternately with the bunches of electrons in the incident beam. By this means the bunching is effectively improved and the output is increased by the energy extracted from the reflected beam. Oscillation will then be produced by very much smaller current than used without reflection. This is due to the fact that an appreciable bunching of the beam is produced by very small oscillatory fields which cause correspondingly small losses. The reflection bunching mechanism comprises the flanges 9 which produce a constant potential along the portion of the beam path passing between the flanges, the resonator being maintained at a positive potential with respect to cathode 3 and the sudden drop in potential is produced by the electrode 5 which is maintained substantially at cathode potential and may be slightly positive zero or negative in potential with respect to cathode. As the amplitude of oscillation increases, the output due to this reflected beam, of course, likewise increases at first and then begins to fall off as the incident beam is "over-bunched."

In this condition, however, the amplitude of the oscillation will be sufficient to cause considerable bunching of the incident electron stream during its first passage through the drift tube and the energy transfer on the first transit will be appreciable.

The operation of the arrangements according to the invention may perhaps be more easily understood by reference to Figs. 2, 3 and 4.

Fig. 2 represents the variation with beam current of the efficiency of a coaxial line type device in which the electron beam is collected after a single transit, the starting current, I_{s1} , being considerable, and the efficiency increasing towards a limiting value e_1 .

Fig. 3 represents the efficiency for the energy extraction from the beam after reflection showing the much smaller starting current I_{s2} (this may easily be made one twentieth of I_{s1} in a practical system) and the ultimate efficiency e_2 .

Fig. 4 shows the efficiency curve actually obtained in practice from the embodiment of the invention described hereinbefore showing both the low starting current of Fig. 3 and the high final efficiency of Fig. 2.

Whilst one embodiment of this invention has been given by way of example, it will be understood that the invention is not limited to the coaxial line type oscillator, but may equally well be applied to the Klystron type of oscillator or to any oscillator in which the electron beam is normally collected after a single transit through the oscillatory fields.

The fields may be produced across apertures in the conducting walls of a high frequency electric resonant chamber, and the beam arranged to pass the said apertures. Each aperture may be in an individual chamber in which case, the chambers are coupled to produce and maintain the electric high frequency oscillations as is well known to those well versed in the art.

What is claimed is:

1. An ultra high frequency apparatus comprising an electron discharge device of the velocity modulation type including an electron gun for producing and directing a beam of electrons along a beam path, said gun including a cathode, and a plurality of means mounted in the order named along said beam path from said gun, means for producing an ultra high frequency electric field for velocity modulating electrons in said beam, means providing a first drift space, means for extracting ultra high frequency energy from said velocity modulated beam and an electrode spaced along said beam from said energy extracting means for reflecting the electrons in said beam back through said extracting means, the space between said extracting means and said reflecting electrode forming a second drift space, said ultra high frequency apparatus further comprising means connected to said energy extracting means for applying a potential thereto and means connected to said cathode and said reflecting electrode for applying a common potential thereto, said last-mentioned potential being negative with respect to said first-mentioned potential and providing an electron transit time from said energy extracting means to said reflecting electrode and return corresponding to an odd number of half cycles of the high frequency field whereby the electrons are bunched when they arrive at the energy extracting means and arrive at said energy extracting means during the intervals between the arrival of bunches in the incident beam.
2. An oscillation generator apparatus of high efficiency comprising an electron discharge device of the velocity modulation type including an electron gun for producing and directing a beam of electrons along a beam path, said gun including a cathode, and a plurality of means mounted in the order named along said beam path from said gun, means for producing an ultra high frequency electric field for velocity modulating electrons in said beam, means providing a first drift space, means for extracting ultra high frequency energy from said velocity modulated beam, means providing a second drift space and an electrode mounted at a distance along said beam path from said extracting means for reflecting the electrons in said beam back through said extracting means, said oscillation generator further comprising means connected to said cathode and said reflecting electrode for applying a common potential thereto and means connected to said means providing said second drift space for applying thereto a potential positive with respect to that of said cathode, said potentials providing an electron time from said energy extracting means to said reflecting electrode and return correspond-

ing to an odd number of half cycles of the high frequency field whereby the electrons are bunched when they arrive at the energy extracting means and arrive at said energy extracting means during the intervals between the arrival of bunches in the incident beam.

3. An oscillation generator apparatus of high efficiency according to claim 2, wherein said means for producing an ultra high frequency electric field, said means providing a first drift space, and said extracting means comprise a coaxial line type resonator with diametrically arranged slots therein aligned with said beam path, said beam path extending through first and second gaps between the inner and outer conductors of said resonator and wherein said means providing a second drift space comprise flanges at the slot in the outer conductor adjacent said second gap, said flanges being parallel to said beam path.
